(57) **CLAIM**

The ornamental design for a piano key overlay tile, as shown and described.

DESCRIPTION

FIG. 1 is a front perspective view of a piano key overlay tile according to one embodiment of the new design;

FIG. 2 is a front view thereof;

FIG. 3 is a back view thereof;

FIG. 4 is a right view thereof;

FIG. 5 is a left view thereof;

FIG. 6 is a top view thereof;

FIG. 7 is a bottom view thereof;

FIG. 8 is a front view of a piano key overlay tile according to another embodiment of the new design;

FIG. 9 is a back view thereof;

FIG. 10 is a right view thereof;

FIG. 11 is a left view thereof;

FIG. 12 is a top view thereof;

FIG. 13 is a bottom view thereof;

FIG. 14 is a front view of a piano key overlay tile according to another embodiment of the designs;

FIG. 15 is a back view thereof;

FIG. 16 is a right view thereof;

FIG. 17 is a left view thereof;

FIG. 18 is a top view thereof; and,

FIG. 19 is a bottom view thereof.
